(57) **CLAIM**

The ornamental design for a stitched clock, as shown and described.

DESCRIPTION

FIG. 1 is a front side top perspective view of my new design with the phantom lines illustrating the round clock portion being environmental structure and forming no part of the claimed design;

FIG. 2 is a front elevational view thereof with the phantom lines illustrating the round clock portion being environmental structure and forming no part of the claimed design;

FIG. 3 is a top plan view thereof with the phantom lines illustrating the round clock knobs being environmental structure and forming no part of the claimed design;

FIG. 4 is a right side elevational view thereof with the phantom lines illustrating the round clock knobs being environmental structure and forming no part of the claimed design;

FIG. 5 is a left side elevational view thereof with the phantom lines illustrating the round clock knobs being environmental structure and forming no part of the claimed design;

FIG. 6 is a back elevational view thereof with the phantom lines illustrating the round clock knobs, battery cover, and alarm switch being environmental structure and forming no part of the claimed design; and,

FIG. 7 is a bottom plan view thereof with the phantom lines illustrating the round clock knobs being environmental structure and forming no part of the claimed design.

The dashed lines shown around the perimeter of the front and rear of the clock case, the dashed lines shown along the edges of the top, bottom and sides of the clock case, as well as the dashed line shown around the opening for the face of the clock represent stitching that forms part of the claimed design.
